CLAIM

The ornamental design for a grill accessory holder, as shown and described.

DESCRIPTION

FIG. 1 is a perspective view of the grill accessory holder in accordance with the present invention;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

The broken lines in the drawings depict portions of the grill accessory holder that form no part of the claimed design.
